UNITED STATES PATENT OFFICE.

NAT H. FREEMAN, OF BOULDER, COLORADO.

APPARATUS FOR ELEVATING WATER.

992,711.

Specification of Letters Patent.

Patented May 16, 1911.

Application filed June 4, 1908. Serial No. 436,587.

To all whom it may concern:

Be it known that I, NAT H. FREEMAN, a citizen of the United States, residing at Boulder, in the county of Boulder and State 5 of Colorado, have invented certain new and useful Improvements in Apparatus for Elevating Water; and I do declare the following to be a full, clear, and exact description of the invention, such as will enable others skilled in the art to which it 10 appertains to make and use the same, reference being had to the accompanying drawings, and to the letters and figures of reference marked thereon, which form a part of 15 this specification.

My invention relates to improvements in apparatus for elevating water through the instrumentality of a series of tanks or receptacles arranged one above another, the 20 said tanks being connected with an air pump whereby the air may be exhausted and the water caused to rise in the tanks in response to the vacuum pull until the tanks are full in which event a valve is automatically operated in connection with each tank whereby 25 communication with the air pump is cut off and the tank opened to the atmosphere, in which event the air pressure within the tank forces the water out and causes it 30 to rise into the next tank, the latter being in communication with the air pump and so on, the water being raised from one tank to another, the distance of the tanks above one another being properly regulated to take 35 advantage of the principle that the weight of the atmosphere will cause the water to rise a certain distance the latter depending to some extent upon the elevation.

My present invention so far as its general 40 features are concerned is substantially similar to the construction disclosed in my prior application Serial No. 419,558, filed March 6th, 1908, but differs therefrom in the means employed for opening and closing the valves connected with the tanks or water receptacles whereby the said tanks are alternately open to the atmosphere and connected with the air pump for exhaust purposes according as it is required to cause the 45 water to enter or pass out of the tank.

In my present construction I employ electro-magnetic means for operating the valves of the various tanks, provision being made in connection with each tank for closing one 50 magnet circuit when the water has reached

a predetermined level in the tank or when the latter is full, and another circuit closed when the water has been driven out of the tank through the weight of the atmosphere. In one case the valve is operated to cut off 60 communication with the air pump or suction pipe, and in the other case the valve is operated to open communication with the suction pipe and cut off communication between the tank and the atmosphere. 65

Having briefly outlined my improved construction, I will proceed to describe the same in detail reference being made to the accompanying drawing in which is illustrated an embodiment thereof. 70

In this drawing, Figure 1 is a side elevation of my improved apparatus illustrating two tanks and their attachments. Fig. 2 is a view of the construction showing two tanks in section and on a larger scale. Fig. 75 3 is a sectional view of an insulating box attached to the top of each tank and in which the contacts are located, whereby the circuits for operating the valve of each tank is controlled. In this view the parts are 80 shown on a larger scale than in Figs. 1 and 2. Fig. 4 is a similar view showing the rod through whose instrumentality the circuits are controlled, in a different relative position from that shown in Fig. 3. Fig. 5 is 85 a detail view showing the electro-magnetic means for operating the valves of the tanks, the valve mechanism being shown in section and the parts on a larger scale. Fig. 6 is a similar view showing the various parts 90 of the mechanism in a different relative position from that shown in Fig. 5.

The same reference characters indicate the same parts in all the views.

Let the numerals 5 and 6 designate two 95 tanks arranged one above another. It must be understood that there may be any desired number of these tanks depending upon the elevation to which the water is to be raised. Each tank is connected with a 100 pipe 7 which is in communication with a casing 8 inclosing a valve 9 having passages 10 and 12 which are both in communication with a space 13 of sufficient size that it remains in communication with the pipe 7 regardless of the position of the valve whereby the pipe 7 alternately becomes a suction pipe and a pipe for introducing atmospheric air to the tank. When the valve is in the 105 position shown in Fig. 5, the passage 10 110

registers with an opening 14 formed in the valve casing and into which is screwed a short open-ended pipe 15 whereby air is allowed to pass into the tank; while when the 5 valve 9 is in the position shown in Fig. 6, the pipe 7 is cut off from communication with the atmosphere and placed in communication with a suction pipe 16 which is threaded into an opening 17^a formed in the 10 valve casing which opening registers with the passage 12, the passage 10 being closed or cut off from communication with the atmosphere. These valves are operated through the instrumentality of a pair of 15 electro-magnets designated 17 and 18 respectively. These magnets are of the solenoid type and their cores or reciprocating bars are designated 19 and 20 respectively. These bars are connected with the opposite 20 extremities of a lever or rock arm 21 whose central portion is made fast to the stem 22 of the valve 9. As these magnets are alternately energized in the manner hereinafter explained, the valve is operated to bring 25 the corresponding tank into communication with the atmosphere or the suction pipe as may be desired. The valve casing as well as the electro-magnets, is mounted upon a stationary frame work 23 having a depend- 30 ing part 24 upon which is fulcrumed as shown at 25, a lever 26 whose opposite extremities are provided with projections 27 and 28. When the magnet 18 is energized, its bar 20 is moved downwardly and acts 35 on the arm 29 of the lever 26 to cause its opposite arm 30 to move upwardly whereby the projection 28 is caused to engage two contacts 31 and 32, thus bridging the space between the said contacts and closing the cir- 40 cuit between two conductors 33 and 34, the latter leading to one terminal of the magnet 17 and the former leading to a contact screw 35 threaded into the insulating box 46 mounted upon a tank 5 or 6 as the case may 45 be. To the inner extremity of the screw 35 is attached a contact 36.

From the opposite terminal of the magnet 17 leads a conductor 37 to a pole 38 of an electric source 39, from whose opposite pole 50 leads a conductor 40 to a conductor 41, one extremity of which is connected with a contact 42 threaded into an insulating box 46. To the inner extremity of this screw is attached a contact 43.

55 When the magnet 17 is energized, the bar 19 is moved downwardly (see Fig. 6) and caused to act on the arm 30 of the lever 26 whereby the projection 28 is disengaged from the contacts 31 and 32 and the contact 60 27 upon the opposite arm of the lever caused to engage two contacts 44 and 45 bridging the space between these two contacts and closing the circuit between a conductor 47 and a conductor 48. The conductor 47, 65 leads to a contact screw 49 threaded into an

insulating box 46. At the inner extremity of this screw is attached a contact 50.

Connected by the opposite terminal of a magnet 18, is a conductor 51, which leads to the conductor 37 connected with the pole 70 38 of a source of electricity 39 as heretofore explained.

Each tank is connected by means of a branch pipe 52 with a standpipe 53. Below each branch pipe 52, is a casing 54 in 75 which is located a ball check valve 55.

In each tank is mounted a rod 56 whose lower extremity is slidably mounted in a hollow plug 57 while its upper extremity passes through an opening 58 formed in the central part 59 of a spider with which the top 60 of the tank is provided. Upon this rod is slidably mounted a hollow float 61. Made fast to the rod near the upper and lower extremities thereof are two stops 62 and 63. As the water rises in the tank the float moves upwardly and when the water has reached a predetermined level in the tank, the float engages the upper stop 62 and as the water continues to rise, the float 90 lifts the rod to the position shown in full lines in Fig. 4 and in dotted lines in Fig. 3 whereby its upper ball-shaped extremity 64 is brought into engagement with the contact 50 and the upper extremity of the contact 43 within the insulating box 46 of the tank. When this occurs the space between the contacts 43 and 50 is bridged and the electric circuit is completed through the coils of the magnet 18. In this event the 100 path of the current may be traced as follows beginning with the contact 50: From the last named contact the current may be said to pass through the screw 49, the conductor 47, the contact 44 and thence through the 105 projection 27, a contact 45, thence through a conductor 48 to one terminal of the magnet coil, and thence through a conductor 51 to a conductor 37, thence to the pole 38 of the electrical source 39 and thence from the 110 opposite pole of the source through a conductor 40 to a conductor 41 and thence to the contact screw 42, to the contact 43 and through the ball extremity 64 of the rod to the contact 50 completing the circuit. As 115 the magnet 18 is energized it acts to draw the bar 20 downwardly and this downward movement, acting on the arm 29 of the lever 26 depresses the last named arm and disengages the projection 27 from the contacts 44 and 45 thus breaking the magnet circuit. This movement of the bar 20, however, due to the energizing of the magnet 18, acts to shift the valve 9 whereby its 120 passage 12 is thrown out of communication with a branch suction pipe 16, while the passage 10 is brought into communication with the atmosphere since the said passage is brought into alignment with the short open-ended pipe 15. The water in the tank 130

is caused to rise by virtue of the exhaustion of the air therefrom due to the tank's communication with a main suction pipe 65 through the branch suction pipe 16. As soon, however, as the water rises to the desired level in the tank as indicated in tank 5 (see Fig. 2), the valve is operated to cut off communication with the suction pipe and open communication with the atmosphere, with the result that the pressure of the atmosphere upon the liquid 66 within the tank, forces the liquid out of the tank through the branch pipe 52 into the standpipe 53 and thence upwardly through the casing 54 opening a valve 55 and causing it to enter the tank 6 above through a branch pipe 52, and hence it will be understood that as the water is driven out of the tank 5 it rises in the tank 6 and when it has become lowered to the desired level in the tank 5, the float 61, engages the stop 63 on the rod 56, and causes the rod to move downwardly disengaging the ball 64 from the contacts 50 and 43 and bringing the said ball into engagement with the contact 36 and the lower extremity of the contact 43. When this occurs the magnet 17 is energized and the path of the current may be traced as follows: From the contact 36 through a screw 35, a conductor 33, to contact 31, thence through the projection 28 to the contact 32 and thence through a conductor 34 to one terminal of the coil of the magnet 17 and thence from the other terminal of the coil through a conductor 37 to the pole 38 of the electric source 39 and thence through a conductor 40 to a contact screw 42 and thence through the contact 43 and the ball 64 to the contact 36 completing the circuit. When this magnet 17 is energized, it acts to move the bar 19 downwardly whereby the lever 26 is actuated to disengage the projection 28 from the contacts 31 and 32 whereby the magnet circuit is broken. The downward movement of the bar 19, however, has been sufficient by virtue of its action upon the lever 21, to shift the valve 9 whereby the passage 10 is cut off from communication with the atmosphere and the passage 12 brought into communication with the branch suction pipe 16 whereby the water is again caused to rise in the tank 5 or 6 as the case may be.

It will be understood that as the water is expelled from the tank 5 it rises in the tank 6 and the float in the last named tank acting upon its rod 56, lifts the same to bring the ball 64 at the upper extremity of the rod into engagement with the contacts 43 and 50 of the tank 6 in the same manner and with the same result heretofore described. In other words the tank 6 will by the operation of its corresponding valve 9 be open to the atmosphere and communication with the suction pipe cut off. As the atmosphere enters the tank 6, the water will be expelled and

caused to enter the tank next above and so on through the entire series of tanks until the water is raised to the desired height.

Having thus described my invention, what I claim is:

1. Means for elevating water, comprising a number of tanks, arranged one above another, a supply pipe in communication with all of the said tanks, a check valve located in the supply pipe below each tank, a float mounted in each tank, a vertically disposed rod actuated by the float, a conduit connected with each tank at one extremity, a valve casing with which its opposite extremity is connected, a valve located within the said casing, the said casing having a port communicating with the atmosphere, a suction pipe also in communication with the casing, electro-magnets for operating the valve, a contact device carried by the vertically disposed rod and arranged to close the circuit through one of the magnets for shifting the valve to communication with the atmosphere when the tank is filled, and to close the circuit through another magnet for shifting the valve to communication with the suction pipe when the tank is empty, and means independent of the said contact device for breaking the circuit of the energized magnet as soon as it has completed the valve movement, the said means comprising a lever actuated by the movable part of either magnet, a circuit connection whereby such movement of the lever breaks the circuit of the energized magnet, substantially as described.

2. Means for raising water, comprising a tank, a supply pipe connected with the said tank, a check valve located within the supply pipe, a conduit connected with the upper part of the tank, valve mechanism connected with the said conduit, a suction pipe also connected with the valve mechanism, two electro-magnets for operating the valve to place the tank alternately in communication with the atmosphere and with the suction pipe through the said conduit, a float located within the tank, a contact device actuated by the float, whereby when the tank is filled the float serves to actuate the said device to close the circuit through one of the magnets for shifting the valve to communication with the atmosphere, while when the tank is empty the device is actuated by the float to close the circuit through the other magnet for shifting the valve to communication with the suction pipe, and a rocking lever arranged to be acted on by the movable part of either energized magnet, whereby the circuit of the actuating magnet is broken simultaneously with the completion of the valve movement, substantially as described.

3. Means for raising water, comprising a number of tanks, arranged one above the

other, a supply pipe connected with the tanks, check valves for preventing the back flow of the water from the tanks, a conduit connected with the upper part of each tank, 5 valve mechanism with which the said conduit is connected, a suction pipe also connected with the said valve mechanism, two electro-magnets for operating the valve of the said mechanism, a float located within 10 each tank, a contact device carried by each float, and arranged to close the circuit through one of the magnets for shifting the valve to communication with the atmosphere when the tank is filled, and to close 15 the circuit through the other magnet for shifting the valve to communication with the suction pipe when the tank is empty, the valve mechanism of two adjacent tanks being reversely actuated at predetermined 20 intervals, a rocking lever arranged to be acted on by the movable part of the energized magnet, and a circuit connection whereby each movement of the lever breaks the circuit of the actuated magnet, substantially 25 as described.

4. The combination with a tank, a water supply pipe connected therewith, a check valve located in the supply pipe for controlling the entrance of water to the tank and 30 its exit therefrom a conduit connected with the upper part of the tank, a valve casing with which the said conduit is in communication, a suction pipe also connected with the casing, a valve piece located in the said 35 casing, being movable to open communication between the conduit and the suction pipe or the atmosphere as may be desired, a lever connected with the valve piece, electro-magnets arranged in operative relation 40 with the opposite extremities of the lever, circuits in which the said magnets are located, a float located within the tank, a contact device actuated by the float to close the circuit through one of the magnets for shifting 45 the valve to communication with the atmosphere when the float is raised and to close the circuit through the other magnet for shifting the valve to communication with the suction pipe when the float is lowered, 50 a rocking lever arranged to be actuated by the energized magnet, and circuit connections whereby such movement of the lever serves to break the circuit of the energized magnet simultaneously with the completion 55 of the valve operating movement, substantially as described.

5. The combination with a tank, a water

supply pipe connected with the said tank, a check valve located within the said supply pipe, for controlling the entrance of water 60 to and its exit from the said tank, an insulating box attached to the top of the tank, a contact located within the box, suction means, valve mechanism for alternately placing the tank in communication with 65 the suction means and with the atmosphere, electro-magnets for operating the valve of the said mechanism, a float located within the tank, a contact device actuated by the float and adapted to act upon the contacts 70 within the insulating box when the float is raised to energize one of the magnets for actuating the valve to place the tank in communication with the atmosphere, and to act upon the said contacts when the float is 75 lowered to close the circuit through one of the other magnets for energizing the same to actuate the valve for placing the tank in communication with the suction means, a rocking lever arranged to be acted upon by 80 the electro-magnets, and circuit connections whereby the movement of the lever breaks the circuit of the magnet simultaneously with the completion of the valve operating movement, substantially as described. 85

6. Means for raising water by alternately exhausting the air from and admitting it to a series of tanks arranged one above another, and so arranged that as the air is entering a lower tank it is exhausted from one above, causing the water to pass from a lower tank to an upper tank, electro-magnets for regulating the supply of air to and exhaust of air from the different tanks a float located 90 within each tank, a contact device actuated 95 by the float to close the circuit through one of the magnets to place the tank in communication with the air when the float is raised and to close the circuit through another magnet for placing the tank in communication with the exhaust when the float is lowered, a lever arranged to be actuated by the electro-magnets, and circuit connections, whereby the said movement of the lever serves to break the circuit of the electro-magnet simultaneously with the valve operating movement, substantially as described. 100 105

In testimony whereof I affix my signature in presence of two witnesses.
